Correction in Design Letters Patent No. 37,184.

It is hereby certified that Letters Patent No. 37,184, granted October 11, 1904, upon the application of Daniel P. Sammis, of Bayonne, New Jersey, for a "Design for an Automobile Body," was erroneously issued to the Riker Motor Vehicle Co., of New York, N. Y., a corporation of New Jersey, as owner of said invention; whereas the patent should have been granted to the *Electric Vehicle Company, of Jersey City, New Jersey, and Hartford, Connecticut*, a corporation of New Jersey, it being sole owner of the entire interest as shown by the assignments of record in the Patent Office; and that the said Letters Patent should be read with this correction therein that the same may conform to the record of the case in the Patent Office.

Signed and sealed this 1st day of November, A. D., 1904.
